UNITED STATES PATENT OFFICE.

EMIL MOONELIS, OF NEW YORK, N. Y.

CIGARETTE-MACHINE.

SPECIFICATION forming part of Letters Patent No. 609,039, dated August 16, 1898.

Application filed February 8, 1896. Renewed January 14, 1898. Serial No. 666,715. (No model.)

To all whom it may concern:

Be it known that I, EMIL MOONELIS, a citizen of the United States, residing at New York, in the county and State of New York, 5 have invented certain new and useful Improvements in Cigarette-Machines, of which the following is a specification.

My invention relates to a machine for making cigarettes singly in contradistinction to those machines that employ a continuous band of paper for the wrapper, and it is intended to be used principally in the making of cigarettes with tobacco wrappers, or what is known in the trade as "all-tobacco" cigarettes. Heretofore the machines which have been designed for this purpose have proved inefficient in many respects, notably in that they were unable to properly handle and roll the wrapper upon the filler and secure even, 10 slightly-uniform, and commercially-marketable articles. The veinous formation of the tobacco-leaf used for wrappers in making these cigarettes requires a delicacy of manipulation which the skilled hand is able to give and which it is my desire in the present machine to simulate, a feature heretofore but partially understood and provided for in all-tobacco-cigarette machines. Ancillary to this 15 main problem of delicately handling the tobacco wrapper are others depending thereon which I have also to an extent provided for and which, together with the main feature, I will discuss in the following specification and will point out in the claims appended thereto the particular novelty for which I desire Letters Patent.

Referring to the accompanying drawings, which form a part of this specification, Figure 1 is a view in side elevation of one embodiment of the invention, illustrating the action of the mechanism by which the tobacco is fed in desirable quantities to the rolling-table. Fig. 2 is a similar view of the opposite side of the machine, showing the manner in which the tobacco is caught, held, and compressed preparatory to being inclosed within the wrapper. Fig. 3 is a view in front elevation, and Fig. 4 is a top plan view representing the action of the machine as illustrated in Fig. 2. Fig. 5 is a view in diagram showing that portion of the feeding mechanism which performs in part the first step in

the operation—that is to say, the feeding of the tobacco to a receiving-chute. Fig. 6 is a similar view showing the discharge of the tobacco from the chute to the pocket of the rolling device or the completion of the first step in the operation. Fig. 7 is a view in diagram illustrating the second step or the shaping of the filler. Fig. 8 is a view in diagram showing the filler taken up, also the application of the wrapper. Fig. 9 is a similar view showing the cigarette passing from the rolling-table to the cutter. Figs. 10 and 11 are similar views in diagram illustrating the 65 action of the cutter, and Fig. 12 is a view in diagram showing the finished cigarette passing through the discharge-chute. Fig. 13 is a fragmentary view in elevation of the actuating mechanism by which the carriage of 70 the feeder is reciprocated. Fig. 14 is a similar view showing the gearing of the feed-rolls. Fig. 15 is a fragmentary view of the mechanism controlling the discharge of the tobacco from the feeder to the rolling-table. 75 Fig. 16 is a similar view of the actuating mechanism of the roller, and Fig. 17 is a fragmentary view of the cutter-actuating mechanism.

The machine comprises a feeder by which 80 the tobacco is delivered in determined quantities, a rolling-table and apron which serve to apply the wrapper, and a cutter for reducing the cigarettes to a desired length, all of which will be taken up and described in sequence.

The feeding mechanism comprises a reciprocating carriage 1, movable in the direction of its length in fixed guides 2, which are supported above a table 3 in any suitable manner, as by brackets 4. The feeder-carriage is movable toward and away from the point of deposit to the forming mechanism hereinafter described. Mounted on rollers 5, journaled between the side plates 6 of the carriage, is 95 an endless belt 7, to which the tobacco in loose form is fed from a supply-hopper and upon which it is carried forward to the feeder-rolls 8 and 9, which are also journaled upon the carriage. By means of a terminal tightener 100 10 the belt is sustained taut, so as to facilitate an equable distribution of the tobacco thereon and insure its proper delivery to the rolls. (See Figs. 1 and 2.) To avoid waste

and retain the tobacco upon the belt, the side plates of the carriage are provided with flaring strips or flanges 11, which project inward beyond the sides and lie just out of contact 5 with the upper surface of the belt. In passing beneath the plain-faced feeder-roll 8 the tobacco is slightly compressed to prevent crumbling and consequent waste and is fed forward into the receiving-chute 12 by being 10 caught by projecting teeth 13 of the feeder-roll proper, 9. (See Fig. 5.)

As will appear later on, the several mechanisms constituting the machine are actuated successively, and it is therefore essential that 15 the feeder-carriage should have an intermittent motion. To effect this, duplicate levers 14 are employed, they being fixed upon a rock-shaft 14^a, journaled in bearings 15 on the machine-frame. These levers extend forward and upward from the shaft and terminate in enlarged heads 16, which are notched to receive gudgeons 17, projecting laterally from the forward end of the feeder-carriage and through which connection horizontal reciprocal motion is imparted to the carriage. 20 From a point at or near the center of this rock-shaft an arm 18 extends downward and is provided with a terminal roller 19, which latter is yieldingly retained in close engagement with a cam 20 upon the main shaft 21 of the machine. As the action of this cam serves only to impart motion in one direction or move the carriage forward in its guides, the reverse movement of the carriage is effected 25 by means of a retractile spring 22, connected with a downward-projecting arm 23 of the rock-shaft. (See Fig. 13.) During such time as the carriage remains at rest or in its normal position—that is, at the limit 30 of its backward movement—the feed mechanism is brought into action through the gearing now to be described. Fixed to the shaft carrying the toothed feeder-roll 9 is a pinion 24, which through the shifting of the 35 carriage is periodically brought into engagement with a continuously-rotating gear-wheel 25, mounted upon a shaft 26, journaled in a stationary bracket 27, extending up from the main frame, motion being imparted to the 40 gear 25, referred to, through a sprocket-wheel 28, keyed upon and revolving with the main shaft, and a sprocket-pinion 29 upon the gear-shaft driven by a chain belt 30. (See Fig. 2.)

Upon the opposite side of the carriage and 45 keyed to the shaft of feeder-roll 9 last mentioned is a worm-pinion 31, which meshes with and drives a worm-gear 32, carried by an angularly-disposed shaft 33, journaled in bracket-bearings 34, secured to the side plate 50 of the carriage. This shaft carries a worm 35, meshing with a worm-wheel 36 upon the shaft of the forward feeder-belt roll 5, upon which latter a gear 37 is fixed and meshes 60 with a pinion 38, carried by the shaft of the plain-faced feeder-roll 8. (See Figs. 1, 4, and 14.) Having geared the feeder-belt and feeder-rolls together in a manner to render

them dependent for motion upon the reciprocation of the carriage, it will be obvious from the foregoing description that the feed mechanism will operate only during the periods that the gear 25 is meshing with constantly-rotating gear 24 and that by changing the form of the cam the period of engagement between the carriage-feed gear and the driving gear from the main shaft may be regulated as desired to increase or decrease the quantity of tobacco fed to the receiving-chute. The periodical discharge of the tobacco from this chute is effected by means of an approximately right-angular lever 39, pivoted at 40 to the carriage track or guide 2, the short arm 41 thereof being bent up and lying in the path of travel of a pin 42, projecting from the side plate 6 of the carriage, and is thereby tripped at 45 each forward movement of the carriage. This motion serves to depress the long arm 43 of the lever, which lies in engagement with an angular extension 44 of a shaft 45, to which shaft the gate 46 of the tobacco-receiving 50 chute is fixed and held normally closed by a plate-spring 47, the action of the lever, however, being sufficient to overcome the resistance of the spring and open the gate, thereby permitting the tobacco contained in the 55 chute to fall upon the rolling-table. (See Fig. 1.)

In being discharged from the feeder-chute the tobacco is caught in a pocket 48, formed by the rolling-apron 49 between the side 100 plates 50 of the rolling-table 51. This apron is secured at its forward end to the terminal vertical face 52 of the arched bed 53 of the table and at its opposite extremity to the rod 54, connecting duplicate rock arms or levers 105 55, which latter are arranged upon opposite sides of the table and pivoted upon a common rock-shaft or with their axes alined, as at 56. Rearward from a point 57 the table-bed is cut away to permit the apron to sag 110 downward to form a receiving-pocket, into which, as before stated, the tobacco is discharged from the feeder-chute. (See Figs. 1, 6, and 16.)

The closing of the chute-gate occurs immediately upon the reversal of the feeder-carriage, which upon reaching the limit of its backward movement brings a tamping device 58 into position to act upon the pocketed tobacco. Mounted in bracketed bearings 59, 115 fixed to one of the feeder-guides 2 of the main frame, is a rock-shaft 60, which, through an integral arm 61, a sliding rod 62, and a cam 63, carried by the main sprocket-wheel 28, receives motion from the main shaft. This motion is transmitted by a terminal depressor-arm 63^a of the rock-shaft to a tamper 64, the rods thereof being slidingly mounted in tubular bearings 65, arranged at the forward end of the feeder-carriage, between the side plates 120 thereof, and supported normally elevated by helical springs 66, which encircle the rods 67. (See Fig. 15.) By the action of the cam the depressor-arm is oscillated and the tamper 125

forced downward against the action of its springs until it enters and compresses the tobacco contained in the receiving-pocket of the rolling-apron, (see Fig. 7,) its retraction being rendered automatic by the resulting expansion of the springs when released by the cam. Extending across the arched bed of the rolling-table and beneath the apron is a roller 68, rotatably mounted and carried in upper terminal bearings 69 of duplicate rock arms or levers 70. An oscillatory movement is imparted to the levers to carry the roller forward and backward over the arched table-bed, and thereby apply the wrapper to the filler contained in the bight. Projecting downward from the axis of these oscillating levers is an arm 71, provided with a terminal roller 72, which is yieldingly retained in close contact with a cam 73 upon the main shaft, a retractile spring 74 being employed to effect a retraction or reversal of the levers and at the same time insure positive action.

Rigid upon and partaking of the motion of the roller-carrying lever-shaft is an arm 75, which in action engages and trips the short arms or an angular extension 76 of the apron-carrying levers 55, causing the latter to move rearward a distance sufficient to draw the apron taut. (See Fig. 16.)

By a proper relative arrangement of the engaging arms just referred to the straining of the apron is made subsequent to the forward motion of the roller, which latter, lying beneath the apron and moving from its normal position to a point 77 on the arched bed-plate of the table, closes the looped pocket (see Fig. 8) by folding the apron upon itself, the contained tobacco being thereby given the desired shape. At a point 78 the pasted wrapper is placed upon the apron and taken up by the action of the roller in a manner to compactly inclose the filler. Upon reaching the limit of their forward movement the levers carry the roller beyond the rolling-table, and thereby discharge the cigarette, which passes therefrom and is caught in semicircular openings of a rotary cutter. (See Figs. 9 and 10.) Simultaneous with the ejection of the cigarette from the rolling-table the apron-carrying levers are brought into action (see Fig. 16) and moved rearward, drawing the apron taut. Upon the further rotation of the cam, however, and acted upon by the retractile spring the levers resume their normal position, thereby reforming the pocket preparatory to the succeeding discharge.

Rotatably mounted in bearings 79, formed in forward-projecting lugs 80 of the side plates of the rolling-table, is a shaft 81, carrying duplicate disks 82, provided with a series of circumferential notches 83, which are alined so as to receive and retain the cigarette as it leaves the rolling-table. (See Fig. 4.) Motion is imparted to the rotary cutter from the cam upon the main shaft through the pawl and ratchet 84, bell-crank lever 85, and connecting-rod 86, between the long arm of the

bell-crank lever and the pawl-carrying arm. (See Fig. 17.) The rotation of the cutter through a half-revolution brings the cigarette 70 into engagement with stationary blades 87, and continued movement serves to reduce the cigarette to a desired length, and thereafter it falls from the cutter upon guides 88 and is by them directed to a suitable receptacle 89, the cuttings falling from the knives into chutes 90. If desirable, chutes 91 may also be placed upon each side of the rolling-table, a catch-tray 92 being provided for the collection of waste.

Having thus described my invention, what I claim, and desire to secure by Letters Patent, is—

1. In a cigarette-making machine, the combination of the cigarette-forming devices, suitable tobacco-feeding mechanism, operating mechanism for the forming devices, and means for automatically throwing the feeding mechanism into and out of gear with the said operating mechanism of the forming devices to operate and arrest the feed with proper relation to the movement of the forming devices, substantially as set forth.

2. In a cigarette-making machine, the combination of the cigarette-forming devices, suitable tobacco-feeding mechanism, a feed-chute constructed to receive the tobacco from the feeding mechanism, operating mechanism for the forming devices, means for automatically throwing the feeding mechanism into and out of gear with the said operating mechanism, and means for automatically discharging the contents of the feed-chute to the forming devices, substantially as set forth.

3. In a cigarette-making machine, the combination of the forming mechanism, with a reciprocating carriage supporting suitable feeding devices, and gearing between the forming mechanism and feeding devices adapted to be thrown into and out of gear by the movement of the carriage, substantially as set forth.

4. In a cigarette-making machine, the combination of the forming mechanism with the reciprocating carriage supporting suitable feeding devices, a feed-chute adapted to receive the tobacco from the feeding devices, gearing between the forming mechanism and feeding devices adapted to be thrown into and out of gear by the movement of the carriage and means operated by the movement of the carriage for discharging the tobacco from the feed-chute, substantially as set forth.

5. In a cigarette-making machine, the combination of suitable forming mechanism, with a reciprocating feeder-carriage, feed-rolls and an endless feed-belt carried by the carriage, and suitable operating-gearing between the forming mechanism and feeding devices thrown into and out of gear by the movement of the carriage, substantially as set forth.

6. In a cigarette-making machine, the combination of suitable forming mechanism, operating means, a constantly-operating gear-wheel 25 driven from the operating means, a

- reciprocating feeder-carriage movable toward and away from the point of deposit, an endless feed-belt supported in the carriage, feed-rolls journaled in the carriage, and a gear 24
5 journaled upon the carriage and geared to the feed rolls and belt and adapted to be thrown into and out of gear with the gear 25 by the movement of the carriage, substantially as set forth.
- 10 7. In a cigarette-machine, the combination of suitable forming mechanism, means for operating the forming mechanism, a continuously-rotating gear-wheel 25 driven therefrom, a reciprocating feeder-carriage movable
15 toward and away from the point of deposit to the forming mechanism, rollers 5 journaled in the carriage, an endless belt 7 supported upon the rollers 5, the worm-wheel 36 and gear 37 on shaft of one roller 5, the smooth
20 feed-roll 8 also journaled in the feed-carriage and provided with a gear 38 meshing with the gear 37, a feed-roll 9 journaled in the carriage and provided with a worm 31 which gears with a worm-wheel 32 carried by
25 an inclined shaft 33 journaled in brackets 34, a worm 35 also carried by said shaft 33 and gearing with the worm-gear 36, and a gear-wheel 24 on the shaft of roll 9 which is adapted to be brought into and out of mesh with
30 the continuously-rotating gear-wheel 25, substantially as and for the purpose set forth.
8. In a cigarette-making machine, the combination with a reciprocating feeder-carriage, feeder mechanism supported upon the carriage and comprising an endless carrier, an evener-roll and a picking-cylinder supported
35 adjacent to the discharge end of the feeder-carriage in working relation to the endless carrier, and gearing for imparting an intermittent motion to the feeding mechanism, as specified.
9. In a cigarette-making machine, the combination with the forming-apron, and the reciprocating feed-carriage, and means for operating it, of a tamper mounted upon the movable carriage and designed to compress the filler within the pocket of the forming-apron, and means for operating the tamper, as specified.
10. In a cigarette-making machine, the combination of a reciprocating feeder, means for operating the feeder, a tamping device carried by the feeder, means for operating the tamping device, a forming-apron, and a forming and wrapper-applying roller, as specified.
11. In a cigarette-machine, the combination of a feeding device, an arched rolling-table, an apron supported above the table and having one end secured to one end of the table, the rock-arms 55 keyed to shaft 56 and supporting the other end of the apron, the rock-arms 70, the apron-roller 68 journaled in the rock-arms 70 above the table and beneath the apron, the rock-arm 76 also keyed to shaft 56, the arm 75 carried by arms 70, and suitable means for operating rock-arms 70, substantially as set forth.

EMIL MOONELIS.
